UNITED STATES PATENT OFFICE

138,718

DESIGN FOR A TWO-PIECE DRESS

Allene Kohlhepp, Miami, Fla.

Application June 19, 1944, Serial No. 114,084

Term of patent 14 years

(Cl. D3—26)

To all whom it may concern:

Be it known that I, Allene Kohlhepp, a citizen of the United States of America, residing at Miami, in the county of Dade and State of Florida, have invented a new, original, and ornamental Design for a Two-Piece Dress, of which the following is a specification, reference being had to the accompanying drawings, forming a part thereof.

In the drawings:

I claim:

The ornamental design for a two-piece dress, as shown.

ALLENE KOHLHEPP.
